GRINDING MACHINE

Emil A. Koether, Baltimore, Md., assignor, by
mesne assignments, to Koppers Company, a
corporation of Delaware

Application July 23, 1936, Serial No. 92,259

12 Claims. (Cl. 51—112)

This invention relates to machines for grinding the opposed faces of flat circular objects such as discs or rings, and is applicable wherever it is necessary to impart to such an article true plane surfaces which are accurately spaced and in strict parallelism with each other.

5 The device is particularly intended for grinding the opposed flat surfaces of piston rings. Since the invention possesses certain peculiar advantages in this field of use, I shall describe it 10 as used in grinding piston rings in order to develop its full utility, but it must be understood that the invention is applicable to the face grinding of any article having opposed parallel flat faces and capable of rotation in the manner 15 hereinafter described. When so used, the device will offer some or all of the advantages which it has in the particular field of piston ring grinding.

Heretofore, face grinding machines have been 20 proposed and, as a matter of fact, utilized, wherein there were two oppositely disposed discs between which the ring or other element to be faced was passed. Such a machine is shown in U. S. Patent No. 1,640,715 to Morton, dated August 30, 25 1927, wherein the proposed grinding elements are single discs.

It has been found in actual practice, not only 30 in the use of this particular machine but with machines of the same order, that trouble is experienced with the discs, owing to the different speeds of the cutting particles on the face of the disc as one approaches the outer circumference of the disc and the inner portion of the disc.

The speed of a cutting particle near the center 35 of the disc is, of course, much slower than that of a portion or particle as the periphery of the disc is approached, and, consequently, the cutting action of the disc will be quite different in those two zones. Due to this variation, the discs wear unevenly and, therefore, even though a ring 40 which is passed between them has imparted thereto a spinning action, the surface finish will not be that which is desired. In other words, parallelism between the ground faces would not necessarily exist.

Furthermore, with the construction about to be 45 described, wherein one or both of the grinding members is composed of an annulus and a disc lying in coplanar relation therewith, it is not essential that the axis of rotation of the opposed 50 discs of the grinder be offset, as in the patent above mentioned.

The main object of the present invention is to 55 provide a grinder, one or both of the grinding members of which comprises a centrally disposed

disc and a ring-shaped disc, the grinding faces of which lie in a common plane or in coplanar relation, and each of which may be rotated independently of the other in the same or reverse direction.

The speed of the component elements of the 5 grinding members may be controlled, and thereby the wear upon said members may be regulated and the effective grinding action likewise regulated and controlled.

Two embodiments of the invention are illustrated 10 in the annexed drawings, wherein:

Figure 1 is a longitudinal horizontal section of the machine with the driving motors for the various grinding elements shown in full;

Fig. 2, a vertical sectional view taken on the line II—II of Fig. 1, with parts broken away; and

Fig. 3, a sectional elevation of a modified arrangement of the opposed grinding member.

Referring first to Figs. 1 and 2, 10 denotes a 20 base or table provided with suitable ways 11, 12, extending longitudinally thereof and adapted to receive the carriages upon which the grinding members and their driving means are mounted. Inasmuch as these parts are duplicates, the same reference numerals will be utilized, with the exponent *a* placed upon those at the left hand side of Fig. 1.

13 denotes a carriage placed upon the ways 11, 25 12 and held in its longitudinal adjusted position by the clamping elements 14, 15. Extending upwardly from the carriage and integral therewith is a standard 16, which throughout its upper portion is hollow or cylindrical in form and is designed to sustain the various driving members for the grinding elements. Said elements are denoted by 17 and 18, the former being ring-shaped or annular and the latter, disc-shaped, with the grinding faces lying in a common plane. Each of the elements 17, 17^a, 18, 18^a, stand directly opposite each other, as will be readily seen upon reference to Fig. 1, and are designed to be driven independently in the same or opposite directions, and at the same or varying speeds.

30 Located within and extending throughout the cylindrical portion of the standard 16 is a shaft 19, said shaft adjacent the grinding elements being formed with a head or face plate 21 to which, in turn, there is secured an annular plate 22 which forms the support and backing for the grinding disc 18, the disc and the backing plate 22 being secured to the face plate 21 by suitable machine screws 23, the heads of which lie within recesses formed within the disc 18.

35 Shaft 19 has mounted thereon ball races 24 and 40

45 50 55 60 65 70 75 80 85 90 95 100

25, the complementary races therefor being denoted by 26 and 27, respectively, which are housed within a sleeve-like member 28. Balls are, of course, mounted between the races just referred to, to form a suitable bearing for the shaft 19 as well as for the sleeve 28. The sleeve is properly supported within the cylindrical member 16 by roller bearings denoted, respectively, by 29 and 31. The latter is held in place by a ring-shaped element 32 secured to the adjacent end of the standard 16 and carries at its inner edge a suitable packing 33 to prevent the outflow of lubricant along the reduced portion of the hollow shaft 28. The races 25 and 27 are held in place with reference to the shaft 19 and the hollow shaft 28 by taking against shoulders formed upon said members against which they are held by a ring-shaped member 34 and a ring-shaped cover plate 35 secured to the exposed end of the hollow shaft 28, said member 35 carrying a packing at its inner edge which cooperates with the reduced portion of the shaft 19.

The hollow shaft 28 at that end adjacent the grinding elements is provided with an integrally formed outwardly extending flange or collar 36, to which is secured a face plate 37, and to this, in turn, is secured a ring-shaped backing plate 38 which forms the support for the ring-shaped grinding element 17. Said element is secured to said member 38 by suitable cap screws 40.

Shaft 19 has secured to its outer end a pulley 39 with which cooperates a belt 41 driven by a variable speed motor or the like 42, which motor may be adjusted to impart the proper tension to the belt and may be likewise shifted laterally by loosening the retaining bolts 43 (Fig. 2) to compensate for adjustment of the grinding members toward and from each other. The outer end of the hollow shaft 28, which is concentric with the shaft 19, carries a pulley 44 which cooperates with a belt 45 to which motion is imparted from a variable speed motor 46.

By the arrangement above described, the grinding element 17 may be rotated in one or another direction, and the same is true of the grinding element 18. Furthermore, the speed of either of them may be changed, and either one or the other driven faster, as occasion may require. By having the inner disc member 18 travel at a speed greater than that of the ring-shaped or annular member 17, the speed of grinding may be said to be equalized as between the two. In other words, as set forth at the outset, where a single disc is employed, the speed of a grinding particle is faster as one approaches the periphery of the disc, whereas with the present structure, this in a sense may be equalized by speeding up the central element 18 or slowing down the ring-shaped element 17.

The elements to be ground or faced may be fed into and between the grinding members in any suitable manner. In the instant case, there is shown a gravity runway, the side plates of which are denoted by 47 and 48. The runway, at the lower portion thereof, is provided with an inclined supporting track or element 49, the upper face whereof stands in alignment with a supporting bar 51 which extends inwardly and between the grinding members. A second bar 52 is located above the parallel with the bar 51, and said bars form in effect the supporting and positioning means for the elements, such as piston rings which are denoted by 53, as they pass between the grinding members. The bars 51 and 52 may be adjusted toward and from each other by right

and left hand screws 54 and 55, the screws being mounted in turn in standards 56 and 57 extending upwardly from the base 10 of the machine.

At the discharge end of the bars 51 and 52 is a pair of spaced plates 58 and 59 (see more particularly Fig. 1), the plates being adjustably supported upon the outwardly extending end of the bars 51 and 52 by bolts which extend through slots formed in the plates and wing nuts 61 mounted upon the outer end of the bolts or screws 10 which pass outwardly through the slots. These may be loosened when it is desired to adjust the sustaining and guide bars 51, 52 toward or from each other, according to the diameter of the article to be acted upon by the grinding members. After the desired adjustment has been effected, by the screws, the wing nuts will be turned up, which, of course, will lock all of the parts against further movement.

Instead of employing oppositely disposed grinding members each having two elements, as above described, to wit, as 17 and 18, respectively, the construction shown in Fig. 3 may be employed wherein a single grinding disc 62 is mounted upon a suitable plate 63 which may be driven from a single motor, said disc standing opposite and in parallel relation to a composite grinding element comprising the ring-shaped member 64 and the centrally located disc-like grinding element 65, which are the same as the members 17 and 18, 30 heretofore described.

Under both of the arrangements above set forth, a spinning action of the ring to be ground will obtain, which action, of course, is desirable in order to insure parallelism of the ground faces. 35

It will be understood that while I have shown and referred to variable speed electric motors for driving the grinding members, any means may be utilized to effect the desired end.

In a broad sense, one of the two grinding elements of a grinding unit may be looked upon as a means for imparting rotative movement to the article being ground, this in addition to its grinding function. So, too, said elements may have different grinding characteristics, as fine and 45 coarse grain surfaces.

What is claimed is:

1. In a grinding machine, the combination of a flat face grinding member; a second member facing the same, one of said members at least comprising two independent concentrically arranged grinding elements rotatable independently of one another about a common axis; and means for rotating said members and the concentrically arranged elements independently of each other. 50 55

2. In a grinding machine, the combination of a flat face grinding member; a second member facing the same and standing and maintained in parallelism thereto, one of said members at least comprising two independent grinding elements, 60 and one of said elements being rotatable within the other; and means for rotating said members independently of each other. 65

3. In a grinding machine, the combination of a flat face disc-like grinding member comprising 65 two concentric rotatable elements, the grinding faces whereof lie in a common plane; a second grinding member of like form, said second member standing opposite to and maintained in fixed spaced relationship with the other member; and 70 means for rotating the various elements independently of each other.

4. In a grinding machine, the combination of two oppositely disposed rotatable grinding members, each grinding member comprising a ring- 75

- like element and a disc-like element located within said ring-like element, the effective grinding faces of said elements being coplanar; means for supporting and maintaining said elements in such relation; and means for independently rotating said elements about a common axis.
5. A machine as set forth in claim 4, wherein means is provided for rotating the grinding elements in diverse directions.
10. 6. A machine as set forth in claim 4, wherein means is provided for varying the rotative speeds of the elements.
15. 7. In a face grinding machine, the combination of two oppositely disposed rotatable grinding members standing in axial alignment; means for rotating the same; and means forming a part of one of said members for imparting a spinning action to an article passing between the oppositely disposed members, said means comprising a third grinding member lying and maintained in a plane common to one of the other grinding members and independently rotatable about the same axis.
20. 8. In a grinding machine, the combination of two oppositely disposed grinding members each rotatable in a fixed plane, and each of said members comprising a plurality of independently rotatable grinding elements, one of said elements being capable of rotation within its companion circumscribing element; and means for rotating said elements independently of each other.
25. 9. A machine as set forth in claim 8, wherein the grinding elements have a common axis of rotation.
10. In a grinding machine, the combination of a flat face grinding member; a second grinding member standing in spaced relation thereto and facing the same, one of said grinding members at least comprising two independent concentrically arranged grinding elements rotatable independently about a common axis; and means for independently rotating said grinding elements at different speeds.
15. 11. In a grinding machine, the combination of a flat face rotatable grinding member; a second grinding member standing in spaced relation thereto and facing the same, said second member comprising a ring-shaped element and a disk-shaped element located within the confines of the ring-shaped element, the grinding faces of said elements lying in a common plane; means for rotating said first named grinding member; and means for independently rotating the elements of the second grinding member at different speeds.
20. 12. In a face grinding machine, the combination of two oppositely disposed rotatable face grinding members standing in axial alignment; means for rotating the same; and means for imparting a spinning action to an article passing between the same, said means comprising a third grinding member lying and maintained in a plane common to one of said face grinding members and independently rotatable about the same axis, at a speed differing from that of its companion member.

EMIL A. KOETHER.
